UNITED STATES PATENT OFFICE.

ARTHUR C. SHOCKEY, OF SHAWNEE, OKLAHOMA.

BRACKET.

1,255,652.

Specification of Letters Patent.

Patented Feb. 5, 1918.

Application filed January 30, 1917. Serial No. 145,562.

To all whom it may concern:

Be it known that I, ARTHUR C. SHOCKEY, citizen of the United States, residing at Shawnee, in the county of Pottawatomie and State of Oklahoma, have invented certain useful Improvements in Brackets, of which the following is a specification, reference being had therein to the accompanying drawing.

10 The present invention relates to an improved bracket for attachment to the ends of box cars and the like for supporting pin lifting rods and holding the handle ends thereof in spaced relation from the adjacent 15 wall of the car to prevent injury to the hand in manipulating the pin lifter.

It is an object of the present invention to provide a bracket which may have a base of any suitable form for attachment to various 20 parts of the car, and which serves as a pivotal support for one end of the pin lifting rod and is a rest or stop for the handle end thereof.

It is another object of the present invention to provide a bracket of this nature which may be cast from malleable iron in a single piece, and a bracket which is strong, durable and easily applied.

The above and other objects and advantages 30 of this invention will be more particularly brought out in the following detailed description of the present preferred embodiment, the same being illustrated in the accompanying drawing wherein,

35 Figure 1 is a perspective view of a bracket constructed according to the present invention and as applied to the end of a box car, and showing a portion of a pin lifter and the hand-hold thereof engaging in the 40 bracket.

Fig. 2 is a side elevation of the same.

Fig. 3 is a top plan view of the bracket showing a part of the pin lifter therein.

Referring to this drawing, 10 designates 45 a car of any suitable form and to which the improved bracket may be applied for supporting one end of the pin lifting rod 11. The rod 11 is provided in the usual manner with a depending hand-hold 12 formed by bending the lever downwardly substantially 50 at the point 13 as shown in the drawing.

In the present embodiment, the bracket is disclosed as having an elongated flat base portion 14 adapted to be placed vertically 55 against the end wall of the car 10 and provided with suitably arranged openings for

accommodating bolts 15 or the like by means of which the bracket is rigidly secured to the car. Preferably, the base plate 14 has its front face cored out to provide a 60 marginal reinforcing flange about the base, and reinforcing bosses about the openings through which the bolts 15 pass. It is apparent that this base plate 14 may be given any suitable length, shape, and thickness in 65 order to adapt the bracket for application to various parts of the car 10.

Outstanding from one edge of the base plate 14 is a supporting lug 16. The lug 16 is flat and is arranged in a vertical plane, 70 having its outer end rounded and provided transversely therethrough with an aperture 17. The aperture 17 is elongated vertically for the reception of the elbow 13 of the pin lifting rod.

The lug or projection 16 is provided at its lower edge with a laterally extending spacing block 18 the same being relatively thick and lying substantially in a horizontal plane. The inner end of the block 18 may be of any 80 suitable form, and is shown in the present instance as being flat. The outer end of the block 18, however, is cored to provide a concavity or seat 19 through which downwardly projects the handle portion 12 of the pin 85 lifting rod. The block 18 forms a stop to prevent the rod 11 from turning sufficiently to bring the hand-hold 12 against the adjacent end of the car, thus insuring the spacing of the hand-hold 12 a distance from the 90 car equal to the length of the block 18. The block 18 is preferably two inches in length so as to provide the prescribed distance between the adjacent part of the car and the hand-hold 12.

95 It is apparent that various changes and modifications may be made in the above specifically described structure of bracket without departing from the spirit of this invention and being restricted only by the 100 scope of the following claims, to adapt the bracket to various conditions of use and to various types of cars upon which the same may be placed, the essential features of the invention being the supporting lug 16 and 105 the spacing block 18 which engages the hand-hold and limits the inward swinging of the same.

I claim:

1. A bracket having an elongated flat base portion cored out to provide a marginal reinforcing flange, a series of openings formed

into the base portion of said bracket, a reinforcing collar formed around each opening flush with the edge of said flange, a forwardly projecting lug formed upon one of the flanges flush with one side of said bracket and having an opening, and a spacing block formed at right angles upon said lug.

2. A device of the kind described consisting of an elongated base plate, a lug formed at right angles thereupon between its ends, a

block formed upon the lower edge of said lug at right angles thereto and laterally of said base plate and extending below said lug, said lug and block having a common back wall, said lug being formed with a vertically disposed elliptical opening and said block being formed with a concave edge in line with said opening.

In testimony whereof I affix my signature.

ARTHUR C. SHOCKEY.
